UNITED STATES PATENT OFFICE

EDWARD B. HUNN, OF ROSELLE, NEW JERSEY, ASSIGNOR TO STANDARD OIL DEVELOPMENT COMPANY, A CORPORATION OF DELAWARE

PROCESS FOR PURIFICATION OF HYDROCARBON OILS

No Drawing.

Application filed July 1, 1927. Serial No. 202,979.

The present invention relates to the art of purifying hydrocarbon oils and more specifically comprises an improved process for sweetening sour distillates of petroleum and the like, as will be fully understood from the following description.

Hydrocarbon oils, in particular the low boiling distillates which make up the gasoline and kerosene of commerce, often contain 10 impurities of a sulfurous nature which it is desirable to remove or modify. The presence of certain impurities is detected by the doctor test which is well known in the art and has been fully described in Technical Paper 323 15 of the United States Bureau of Mines, page 83. Oils which fail to pass this test are known as sour oils and it is customary to sweeten such oils by a treatment with doctor solution, which is a solution of litharge in aqueous 20 caustic soda, as is well known.

In carrying out the sweetening process the oil is agitated with doctor solution. It is customary to add flowers of sulfur to precipitate the lead as lead sulfide and to allow the 25 aqueous and oily layers to separate. There is considerable difficulty in adding the exact quantity of sulfur and if an excess is added, the oil will be corrosive, which is undesirable.

My invention comprises adding a low boiling 30 alkyl disulfide to the oil instead of flowers of sulfur and I have found that by such addition a precipitate is formed which may be removed, and that the remaining oil is sweet to the doctor test. An excess of disulfide is not detrimental either in respect to 35 sourness or corrosion.

I have found that methyl, ethyl, or propyl disulfide or a mixture of two or more of these sulfides is satisfactory for my process and 40 that such disulfides may be added to the oil before or after the doctor treatment. The reaction is relatively slow but may be hastened by warming.

The precipitate formed by the addition of 45 alkyl disulfide is found to contain the corresponding alkyl-lead mercaptide with or without lead sulfide, depending on the particular impurities in the sour oil.

My process may be carried out in any form 50 of treating apparatus known in the art,

either batch or continuous. The disulfide may be added to a part of the oil, which is then agitated with the bulk of the oil, if so desired. In treating very sour oils where the quantity of disulfide required is large, I contemplate adding sulfur according to the present practice, but in quantity insufficient to completely sweeten the oil, then to complete the process by addition of alkyl disulfide, as described. 55

As an example of my process, 250 cc. of sour cracked naphtha having a gravity of 49.7° A. P. I. and a sulfur content of .265% is agitated about 5 minutes with doctor solution. The oil is separated and .20 cc. of 60 N-propyl disulfide added. The mixture is agitated and after standing for several hours, a dark yellow precipitate separates and is filtered from the oil, which now passes the doctor test and is non-corrosive, as indicated 65 by the fact that it will not tarnish a strip of bright copper submerged in the oil for one-half hour at 212° F. The sulfur content of 70 the oil is .288%.

As a second example of my process, 200 cc. 75 of sour water white distillate, 42.5° A. P. I., with sulfur content of .210%, is treated with doctor solution and after separation of the aqueous layer .20 cc. of methyl disulfide is added. The oil is heated in a steam bath and 80 after six hours the precipitate is filtered off. The color of the oil is found to be improved, it passes the doctor test and is non-corrosive according to the test specified in the first example. The sulfur content is now .244%. 85

My invention has been described particularly in respect to the sweetening of gasoline and kerosene from petroleum but it is applicable to the treatment of other hydrocarbon oils, such as natural gas gasoline and liquid products extracted from refinery gas, coal gas, and the like. My invention is not to be limited by any theory of the mechanism of the reaction nor by any example given merely by way of illustration, but only by 90 the following claims, in which I wish to claim all novelty inherent in my invention.

I claim:

1. The process of improving light hydrocarbon distillate, comprising treating the dis- 100

tillate with doctor solution and then adding a low boiling alkyl disulfide to the distillate.

5 2. The process of improving light hydro-carbon distillate, comprising treating the distillate with doctor solution, adding a low boiling alkyl disulfide, and separating the precipitate formed thereby from the distillate.

10 3. The process of sweetening light hydro-carbon distillate, comprising treating the distillate with doctor solution, adding an alkyl disulfide characterized by the fact that the corresponding alkyl lead mercaptide is insoluble in distillate, and filtering the precipitated lead mercaptide from the distillate.

15 4. A process of sweetening light hydro-carbon distillate, comprising treating the distillate with doctor solution, adding thereto a mixture of organic disulfides comprising methyl, ethyl and propyl disulfides, and removing the precipitate formed thereby.

20 5. The process of sweetening light hydro-carbon distillate, comprising treating the distillate with doctor solution, adding sulfur to the distillate less than sufficient to completely precipitate the lead as lead sulfide, adding a low boiling alkyl disulfide to the distillate and separating the precipitate so formed.

25 6. The process of sweetening light hydro-carbon distillate, comprising treating the distillate with doctor solution, withdrawing the aqueous spent doctor solution, adding a low boiling alkyl disulfide to the distillate and separating from the distillate the precipitate so formed.

30 7. The process according to claim 3, in which the reaction is carried out at a temperature above normal atmospheric temperature.

35 40 8. The process of sweetening light hydro-carbon distillate, comprising adding a low boiling alkyl disulfide to the distillate and then treating with doctor solution in the presence of the alkyl disulfide.
